ELEVATOR DOOR GUIDE

Ralph L. Henry, Detroit, Mich., assignor to Hen-
rite Products Corporation, Ironton, Ohio, a
corporation of Ohio

Application March 8, 1932, Serial No. 597,464

5 Claims. (Cl. 16—93)

This invention relates, generally, to elevators; and the invention has reference, more particularly, to a novel form of improved guide for use on elevator doors, such as hatchway doors and car doors, the same being also adapted for use on all sliding doors.

As an elevator car travels up and down its hatchway, the movement of the car creates a region of increased pressure in advance of the car and a region of reduced pressure behind the car. These variations in pressure, created by the movement of the car, cause elevator doors, such as hatchway doors and car doors, to rattle or vibrate. Rattling is very disturbing and objectionable, the same being especially noticeable in buildings having high speed elevators. Elevator doors as heretofore constructed, merely employ metal guide shoes which ride in guide grooves provided in the metal threshold plates of floor landings and elevator cars. The metal to metal contact of the guide shoes with the sides of the guide grooves, and especially the inherent looseness of the guide shoes within the guide grooves of the threshold plates, tends to greatly increase the rattling noise.

This application is a continuation-in-part of applicant's copending application, Serial No. 515,034, filed Feb. 11, 1931, for Elevator door guide, wherein there is disclosed and claimed, a novel form of door guide, which, when applied to an elevator door, substantially eliminates rattling or other noise of the door.

The principal object of the present invention is to provide a novel elevator door guide of the general type disclosed in my copending application, but which embodies certain improvements and changes, the most pronounced of which lies in the provision of means for preventing the parts of the door guide from becoming accidentally separated prior to or during the installation of the guide upon an elevator door, which accidental separation of the guide parts might otherwise lead to loss of a part of the guide as well as slowing up of the installation.

Another object of the present invention lies in the provision of the novel elevator door guide of the above character, having cooperable, interlocking elements to prevent the accidental separation of the parts of the guide, the said door guide having parts that are resiliently urged into engagement with the sides of the door guide groove to thereby take up any looseness or wear and prevent rattling of the door.

Still another object of the present invention is to provide a novel elevator door guide which is

of simple construction and which is reliable and has a long life in use.

Other objects of this invention, not at this time more particularly enumerated, will be clearly understood from the following detailed description of the same.

The invention is clearly illustrated in the accompanying drawings, in which:

Fig. 1 is a fragmentary, sectional view and illustrates an elevator car door equipped with one form of the novel elevator door guide of the present invention.

Fig. 2 is a fragmentary, sectional view taken substantially along line 2—2 of Fig. 1 looking in the direction of the arrows.

Fig. 3 is a perspective view looking at the bottom of the hatchway door of Fig. 1 with the door removed from its guide groove.

Fig. 4 is a plan view of a modified form of guide shoe.

Fig. 5 is a sectional view taken substantially along line 5—5 of Fig. 4.

Fig. 6 is a view similar to Fig. 4 but of a slightly modified form of construction.

Fig. 7 is a sectional view taken substantially along line 7—7 of Fig. 6 looking in the direction of the arrows.

Fig. 8 is a plan view of a further modified form of guide shoe.

Fig. 9 is a perspective view of the structure shown in Fig. 8.

Fig. 10 is a view similar to Fig. 8 and illustrates a slightly modified form of construction.

Fig. 11 is a view similar to Fig. 8 but illustrates another modified form of construction; and

Fig. 12 is a perspective view of the structure shown in Fig. 11.

Similar characters of reference are employed in all of the above described views, to indicate corresponding parts.

Referring now to Figs. 1 to 3 of the drawings, the reference numeral 1 designates the floor of an elevator car having a door 2 which is illustrated as equipped with one form of the novel door guides of the present invention, which guide is designated as a whole by the reference numeral 3. Each car door as well as each hatchway door is ordinarily equipped with two or more of the guides 3, which guides are secured to the bottoms of the doors and project into suitable guide grooves provided in the threshold plate 4 of the elevator car and in the threshold plate or sill of the hatchway landing (not shown).

In Fig. 1, the threshold plate 4 is illustrated as of the self-cleaning type and has guide bars 5.

which are engaged by the door guides 3. As especially shown in Figs. 2 and 3, each of the door guides 3 comprises a body member 6 of prismatic shape, the same being of rectangular cross section and having beveled surfaces 7 at its ends. The end portions of the body member 6 are provided with vertical apertures for receiving screws 8 for attaching the door guide to the bottom of the door 2. The heads of the screws 8 are illustrated 10 as countersunk in the body member 6.

The body member 6 is illustrated as provided with a recess 9 at one side thereof for receiving a guide member 10 therewithin. The guide member 10 is of substantially rectangular shape, as viewed in elevation, and the upper part of this guide member is provided with oppositely directed 15 end projections 11. The ends of projections 11 are beveled as indicated at 12 so as to give the upper part of the member 10 a keystone or wedge shape, as viewed in plan, see especially Fig. 2. The upper part of body member recess 9 is elongated to conform to the elongated upper part of guide member 10, the said recess providing supporting shoulders 13 upon which the projections 20 11 are adapted to rest, thereby supporting the guide member 10 upon the body member 6.

The upper enlarged part of the body member recess 9 has beveled end walls 14 of substantially the same inclination as the beveled ends 12 of the guide member 10. The length of the upper part of guide member 10 is somewhat less than the length of the upper enlarged part of recess 9 so as to permit limited transverse movement of guide member 10 with respect to the body member. Thus, the guide member 10 may move outwardly of recess 9 a limited distance as shown 30 in Fig. 3. Transverse movement of the guide member 10 outwardly of recess 9 is limited by the beveled ends 12 contacting with beveled end walls 14 of the recess 9. A bowed spring 15 is contained within recess 9 of the body member and rests upon shoulders 13 of the body member. Spring 15 acts to urge the guide member 10 outwardly of recess 9, thereby tending to position 35 guide member 10 in its outermost position, as illustrated in Fig. 3, with the beveled ends 12 abutting the beveled end walls 14. The interlocking action of the ends 12 with the end walls 14 serves to prevent the complete escape of the guide member 10 from recess 9 under the action of spring 15 and hence the guide member 10 and the body member 6 will not be accidentally separated prior to or during the installation of the same upon a door.

To install the door guide on an elevator door, it is merely necessary to insert the screws 8 into the apertures provided in body member 6 and to thread these screws upwardly into the door, as shown in the drawings. When the door guide is inserted into the threshold plate guide groove, the spring 15 serves to urge the body member 6 and the guide member 10 outwardly in opposite directions and against the guide bars 5, thereby guiding the door 2 in its motion and preventing the rattling of the same. Owing to the action of the spring 15 in tending to move the members 6 and 10 outwardly and away from one another, these members automatically adjust themselves to any width of guide groove, and always engage the sides 60 of bars 5 of the guide groove, thereby preventing rattling or vibration of the door in use.

Preferably the body member 6 and the guide member 10 are made of a molded material having self-lubricating properties, which molded material may consist of asbestos, graphite and a con-

densation product, such as bakelite. Such a suitable molded material has been described in my above mentioned copending application. It is to be understood, however, that these members 6 and 10 may be made of other materials, such as of wood, composition or even of metal. Since spring 15 serves to hold the members 6 and 10 in engagement with the sides of the guide groove at all times, there is no possibility of rattling or jarring even if these members are made of metal, 10 and consequently metal may be used for this purpose. The reason that ordinary metal guide shoes rattle is because they necessarily have a loose fit in their guide grooves and slap from one side of the guide groove to the other in use, 15 thereby causing the rattling noise of the doors. When using the novel guide of the present invention, however, all transverse motion of the door guide and of the door is substantially prevented, and consequently rattling is eliminated. 20

The novel guide illustrated in Figs. 4 and 5 also is provided with a body member 17 having beveled ends 7 and apertures 16 for receiving attaching screws. The body member 17 has a recess 18 therein extending from the top of this body 25 member almost to the bottom thereof, thereby providing a bottom ledge or wall 20 for supporting a guide member 21 positioned within recess 18. The guide member 21 is of rectangular shape and has oppositely directed projections 22 at its 30 ends, which projections are adapted to cooperate with similar projections 23 formed on the body member 17 at the ends of recess 18. A bowed leaf spring 15 is also contained within recess 18 and presses at its ends upon the inner wall of recess 35 18 and at its center upon guide member 21, thereby urging this guide member outwardly of recess 18. The outward movement of guide member 21 under the action of spring 15 is limited by projections 22 of this member engaging projections 23 40 of the body member. Thus, the interlocking action of projections 22 and 23 prevents the accidental separation of members 17 and 21 and thereby prevents loss of member 21. It will be noted that the bowed spring 15 renders the guide 45 member 21, as well as the guide member 10 of Fig. 2, self-aligning so that these guide members will automatically align themselves with their respective guide grooves.

The guide construction shown in Figs. 6 and 7 50 is similar to that shown in Figs. 4 and 5 with the exception that coil springs 19 are used to urge the two members 17 and 21 apart. Coil springs 19 have their inner ends frictionally retained within circular recesses 24 provided in body member 17. 55 The bottom ledge or wall 20 supporting the guide member 21 in Figs. 6 and 7 is provided with an aperture 25 to allow the escape of dirt or other foreign material which might otherwise collect within recess 18 and tend to interfere with the 60 movement of guide member 21 within this recess. It will be apparent that the structure of Figs. 4 and 5 may similarly be provided with an aperture similar to aperture 25, if desired.

In the form of the invention shown in Figs. 8 65 and 9, the door guide is illustrated as provided with two guide members 21 arranged at opposite sides of the body portion of the guide. The door guide in these figures has a body member 26 which is similar in external shape to the body member 17 70 of Figs. 4 to 7, the said body member having beveled ends 7 and apertures 16 for receiving attaching screws. Body member 26 is provided with two recesses 21 extending inwardly from the sides thereof, which recesses are similar to recesses 18 75

of the guides shown in Figs. 4 to 7 and have bottom supporting ledges or walls 31 for supporting the guide members 21.

The recesses 27 at opposite sides of the body member 26 are separated by a vertical partition 28 against which the ends of two springs 15 bear. The bowed central portions of these springs bear respectively against the respective guide shoes 21, 21. The guide shoes 21, 21 are provided with oppositely directed projections 22 at their ends which cooperate with projections 23 formed on the body member 26 to thereby prevent the escape of guide members 21 from their respective recesses. The use of the two guide members 21 at opposite sides of the elevator door guide, enables both sides of the guide to be self-aligning or to adjust itself automatically to both sides of the guide grooves. In this form of the invention, the body member 26 is preferably made of metal, and the guide members 21 are preferably made of molded material having self-lubricating properties, such as the molded material described in my aforementioned copending application. It is obvious, however, that both the body member and the guide members may be made of the same material, if desired, which may be either metal, composition, wood or other suitable material.

The form of the invention shown in Fig. 10 is similar to that shown in Figs. 8 and 9 with the exception that coil springs 30 are used to effect the outward expansion of guide members 21. Coil springs 30 have their inner ends frictionally retained within circular recesses or depressions provided in partition 28 and their outer ends bear against the guide members 21. In this figure the bottom ledges or walls 31 supporting the guide members 21 are illustrated as apertured at 32 to enable the escape of dirt or other foreign material. It will be apparent that the form of the invention shown in Figs. 8 and 9 may also be provided with these self-cleaning apertures 32, if desired.

In the form of the invention shown in Figs. 11 and 12, the intermediate partition is done away with and the body member 33 is provided with a simple transverse recess 34 within which is mounted the two guide members 21. Bowed springs 37, 37 are shown mounted within the recess 34 and act in opposite directions to urge the respective members 21, 21 outwardly. The end portions of springs 37, 37 abut one another and are slidably received in conforming recesses 38 provided in the body member 33. The bottom wall 35 of the body member 33 is illustrated as provided with an aperture 36 to enable the escape of dirt or other foreign material.

It will be apparent that a single integral spring may be used in lieu of springs 37, 37 in the form of the invention shown in Figs. 11 and 12. It will be noted that all the novel guide members shown in the drawings, are self-adjusting and expansible to conform to the guide grooves in which they move. The guides are adapted to be attached to the elevator doors by screws in the same manner as ordinary metal guides, and therefore require no additional installation expense. Owing to the inner interlocking arrangement of the body and guide members of the several guides, there is no possibility of these members becoming separated and individually lost prior to or during installation on the job. Also, inasmuch as the spring or springs in all forms of the invention act directly between the body member and the guide member or members, any tendency of the door and hence of the

body member to vibrate is directly resisted by the compression of the spring or springs.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

What is claimed is:

1. A sliding door guide adapted to ride in a door guide groove, said door guide comprising, a body member arranged to be fixedly secured to the bottom of a door for projecting into the guide groove thereof, said body member having a recess extending transversely inwardly from one side thereof, said recess being open at its top, said body member being formed with a bottom wall underlying said recess, a guide member positioned within said recess and resting upon said bottom wall, and spring means positioned within said recess and interposed between said body and said guide member for urging said guide member outwardly into engagement with the side of the door guide groove.

2. A sliding door guide adapted to ride in a door guide groove, said door guide comprising, a body member arranged to be fixedly secured to the bottom of a door for projecting into the guide groove thereof, said body member having a recess extending transversely inwardly from one side thereof, said recess being open at its top, said body member being formed with a bottom wall underlying said recess, a guide member positioned within said recess and resting upon said bottom wall, spring means positioned within said recess and interposed between said body and said guide member for urging said guide member outwardly into engagement with the side of the door guide groove, said bottom wall having an aperture therein to permit the escape of foreign matter, and means for limiting the outward movement of said guide member, said bottom wall and the bottom of the door serving to prevent vertical movement of said guide member.

3. A sliding door guide adapted to ride in a door guide groove, said door guide comprising, a body member arranged to be fixedly secured to the bottom of a door for projecting into the guide groove thereof, said body member having recesses extending transversely inwardly from the sides thereof, said recesses being open at their upper sides, said body member having a bottom wall for closing the lower sides of said recesses, a pair of guide members, each one of said guide members being positioned in a respective one of said recesses and spring means positioned within said recesses for urging said guide members outwardly thereof and into engagement with the sides of the guide groove.

4. A sliding door guide adapted to ride in a door guide groove, said door guide comprising, a body member arranged to be fixedly secured to the bottom of a door for projecting into the guide groove thereof, said body member having recesses extending transversely inwardly from the sides thereof, said recesses being open at their upper sides, said body member having a bottom wall for closing the lower sides of said recesses, a pair of guide members, each of said guide members being positioned in a respective one of said recesses and resting upon said bottom wall,

- spring means positioned within said recesses for urging said guide members outwardly thereof and into engagement with the sides of the guide groove, and interlocking projections formed on said guide members and on said body member for limiting the outward movement of said guide members with respect to said body member, said bottom wall being apertured to permit the escape of foreign matter from within said recesses.
- 10 5. A door guide for sliding doors comprising, a member attached to the edge of the door for projecting beyond the periphery of the door and into a guideway narrower than the door for

guiding the door in its movement, said member having a transverse recess extending inwardly from the outer wall thereof and having a transverse supporting wall, another member slidably mounted in said recess on said supporting wall 5 for movement transversely with respect to the door, said last named member having a flattened surface for engaging the side of the guideway, and a resilient spring element interposed between said members for urging the same apart, 10 whereby said members cooperate in guiding the door in its movement.

RALPH L. HENRY.
